UNITED STATES PATENT OFFICE.

MICHAEL F. A. O'TOOLE, OF BALTIMORE, MARYLAND.

SHIPPING-CRATE.

1,383,561.

Specification of Letters Patent.

Patented July 5, 1921.

Application filed February 28, 1920. Serial No. 361,984.

To all whom it may concern:

Be it known that I, MICHAEL F. A. O'TOOLE, a citizen of the United States of America, residing at Baltimore, in the city 5 of Baltimore and State of Maryland, have invented certain new and useful Improvements in Shipping-Crates, of which the following is a specification.

This invention relates to certain new and 10 useful improvements in shipping crates particularly adapted for the shipment of fowl or the like and capable of being readily folded for compact arrangement within a small space when not in use as well as capable of being quickly and easily set up in 15 open or expanded condition when required for use.

The principal object of the present invention is to provide a shipping crate of the 20 above character which embodies a bottom member having side and end walls foldable upon horizontal pivots thereon and connected with a top wall member in a novel manner, both slidably and pivotally so that 25 the crate may be readily collapsed or expanded by the mere manipulation of the top member of the crate.

A further object of the invention is to 30 provide improved means for slidably and pivotally connecting the top member of the crate to the side members thereof for carrying out the operation set forth above.

With the above and other objects in view, 35 the invention consists in the novel form, arrangement and combination of parts hereinafter more fully described, shown in the accompanying drawings, and claimed.

In the drawings, wherein like reference 40 characters indicate similar parts throughout the several views,

Figure 1 is a top plan view, partly broken away, of a shipping crate constructed in accordance with the present invention and shown in collapsed condition,

45 Fig. 2 is a side elevational view of the device shown in Fig. 1.

Fig. 3 is an end elevational view thereof,

Fig. 4 is an enlarged sectional fragmentary view taken substantially upon line 50 IV-IV of Fig. 1,

Fig. 5 is a view similar to Fig. 4 taken substantially upon line V-V of Fig. 1,

Fig. 6 is a view similar to Fig. 5 taken upon line VI-VI of Fig. 1,

55 Fig. 7 is a view similar to Fig. 6 taken upon line VII-VII of Fig. 1,

Fig. 8 is an enlarged fragmentary view partly in elevation and partly in vertical section, of a corner portion of the crate shown in Fig. 1, when in expanded condition, the parts being seen substantially as they would appear when taken upon line VIII-VIII of Fig. 9,

Fig. 9 is a fragmentary elevational view of the device shown in Fig. 8,

Fig. 10 is a view similar to Fig. 8 but taken upon a line of section at right angles to the same,

Fig. 11 is a perspective view partly broken away, of an end portion of one of 70 the end walls of the crate,

Fig. 12 is a fragmentary perspective view of a corner portion of the top member of the crate,

Fig. 13 is a view similar to Fig. 12 of the 75 bottom wall of the crate and showing the hinge members for the side and end walls of the crate,

Fig. 14 is a fragmentary perspective view of the crate shown in Fig. 1 as the same 80 appears when partially expanded,

Fig. 15 is a fragmentary perspective view of a portion of one of the side wall members of the crate,

Fig. 16 is an enlarged fragmentary perspective view showing adjacent parts of the top wall member of the crate and one side wall member thereof with the connecting link therefor which permits the pivotal and sliding movement of the top wall member, 85 and,

Fig. 17 is a fragmentary perspective view of one rung of one of the side walls of the 90 crate and the associated catch for retaining the crate in a collapsed condition,

Referring more in detail to the several views, the present invention broadly comprises a bottom wall or member 5 which may be of any desired construction but which is preferably rectangular in plan and substantially solid throughout. The bottom wall 5 has ribs 6 rigidly fastened longitudinally thereon adjacent its opposite side edges, and suitable angular brackets 7 are fastened upon the opposite ends of these 105 ribs and are provided with perforations 8 for reception of the pivot pins 9 which are carried by suitable brackets 10 fastened rigidly upon the ends of the lower rail 11 of each end wall of the crate so as to pivotally mount said end walls for swinging upwardly to a vertical position or downwardly

to a horizontal position upon the upper surface of the bottom wall 5 as is usual in this class of devices. The ribs 6 also have suitable leaf hinges 12 fastened thereto adjacent 5 the brackets 7 which are also fastened to the lower rails 13 of the side walls of the crate so as to pivotally mount the latter for swinging downwardly upon the end walls of the crate or for swinging upwardly 10 to a vertical position when the crate is expanded. The side and end walls of the crate are preferably of the ordinary construction embodying longitudinal parallel rails, the top rail of the end walls being indicated at 14 and the top rails of the side walls being indicated at 15, the two rails of the side and end walls being connected by transversely disposed bars 16 in the usual way. It will thus be seen that the side and 15 end walls of the crate are foldable upon horizontal pivots so that the end walls may first be folded inwardly upon the upper surface of the bottom wall 5, after which the side walls of the crate may be folded onto 20 the end walls.

25 The top wall or member of the crate is of the same general shape and size in plan as the bottom wall 5, but is preferably composed of a rectangular frame 17, the end members of which are connected by longitudinal rails 18 which are arranged in spaced parallel relation between the side rails of the frame 17, which side rails of the frame 17 are connected by transverse rungs or 30 spaced bars 19 that also pass through aligned perforations provided in the rails 18 of the top wall. The rungs 19 are omitted between the rails 18 centrally of the top member of the crate in the usual manner to form an 35 opening through which the fowl may be introduced into the crate, said opening being closed by the ordinary form of closure 20 which is hinged at one end and slidable upon one of the rungs 19 so that the coil spring 40 21 may slide said closure for engaging the projecting end 22 of one of the rungs in the socket 23 of the closure 20 for locking the latter in closed position. The above described structure is substantially entirely old 45 in the art with the possible exception of the form of hinge connection between the end walls of the crate and the bottom wall thereof and will be readily understood by those skilled in the art.

50 55 A plurality of hooks 24 preferably formed from wire are pivotally mounted upon substantially the central rungs 16 of the side wall members of the crate so that the same may be swung upwardly to engage over the 60 rungs 19 of the top member of the crate which are immediately thereabove when the crate is collapsed so as to hold the same in this condition. The manner in which these hooks are formed and their relation to the 65 rungs is clearly shown in Figs. 4, 6, and 17.

It will be understood that in expanding the crate to its opened-up condition, the side walls thereof are first swung upwardly, and then the end walls thereof are swung upwardly until the ends of the rails 11 and 14 of said end walls engage the end rails 15 of the side walls of the crate so as to hold said side walls vertically disposed. The frame 17 of the top wall of the crate is provided with a plurality of perforations 25 which are aligned with similar perforations 26 in the end walls of the crate when the latter are vertically disposed, and suitable pins 27 are passed through these perforations for holding the crate in an expanded condition.

Angular wire loops or links 28 are arranged adjacent the corners of the crate, and each loop 28 loosely connects an adjacent pair of the bars 16 and 19 of the side and top wall members of the crate respectively as more clearly shown in Figs. 5, 7, 8, and 16, so that the top wall member of the crate is at all times slidably and pivotally connected to the side walls of the crate. By shifting the top wall of the crate laterally relative to the rest of the crate, the loops 28 at one side of the crate, are brought adjacent the top rail 15 of one of the side walls, whereupon a lifting force is exerted upon the top wall so as to swing the said side wall upwardly as shown in Fig. 14. The top wall of the crate is then shifted laterally in the opposite direction and simultaneously swung upwardly at its opposite side so as to cause the other side wall of the crate to be lifted to a vertical position. When the above takes place, the loops or links 28 embrace the top rails of the side walls as shown in Fig. 8. When the loops 28 are positioned as shown in Fig. 8, a portion of each of the same lies between one of the top rails 15 and the adjacent side rail of the frame 17, and in order to accommodate these portions of the links between the rail 15 and the adjacent rail of the frame 17, said rails 15 are provided with transverse parallel grooves 29 which permit the top wall of the crate to rest upon the side and end walls of the crate even in view of the fact that the links 28 are positioned so as to have a portion of the same lie between the side walls and the top.

If it is desired to collapse the crate, the pins 27 are removed and the end walls may be readily swung inwardly upon the bottom wall 5 as illustrated with respect to one of the end walls in Fig. 14. The top wall of the crate is then slid laterally in one direction and allowed to fall at one side so that the walls assume the relative position as is also shown in Fig. 14. The top wall is then slid laterally in the opposite direction for swinging the other side wall downwardly until said other side wall also lies upon the end walls and the top wall lies upon the side walls as illustrated in Figs. 2 and 3. With

the side, end and top walls collapsed in this condition, it will be seen that the hooks 24 may be readily swung upwardly to the full line position of Fig. 6 so that each of the 5 same engage over one of the rungs 19 for maintaining the crate in collapsed condition.

From the foregoing, it will be seen that I have provided an extremely simple form of shipping crate which may be readily collapsed and expanded by manipulation of the 10 top wall member thereof, the same being made possible by the novel form of connection between the side walls and top wall of the crate as above outlined.

15 It is believed that the construction and manner of use as well as the advantages of the present invention will be readily understood and appreciated by those skilled in the art from the foregoing description.

20 It will be understood that minor changes may be made in the various parts as well as the specific combination and arrangement thereof shown and described without departing from the spirit of the invention as 25 claimed.

What is claimed as new is:

1. A collapsible shipping crate comprising a bottom wall member having end and side walls hinged thereto upon horizontal 30 pivots, a top wall member, and means operatively connecting said top wall member to the side wall members whereby manipulation of the top wall member will effect raising and lowering of said side wall members 35 to their collapsed or expanded position, said means comprising loops loosely and slidably connected to the top and side wall members.

2. A collapsible shipping crate comprising a bottom wall member having end and side 40 walls hinged thereto upon horizontal pivots, a top wall member, and means operatively connecting said top wall member to the side wall members whereby manipulation of the top wall member will effect raising and lowering of said side wall members to their collapsed or expanded position, said side and 45 top wall members including transverse bars or rungs, and said means including loops slidably loosely connecting pairs of said 50 rungs of the side and top wall members.

3. A collapsible shipping crate comprising a bottom wall member having end side walls hinged thereto upon horizontal pivots, a top 55 wall member, means operatively connecting said top wall member to the side wall members whereby manipulation of the top wall member will effect raising and lowering of said side wall members to their collapsed or expanded position, said side and top wall 60 members including transverse bars or rungs,

said means including loops slidably loosely connecting pairs of said rungs, and hooks pivoted upon rungs of said side wall members and arranged to swing to engage rungs of the top wall member for holding the crate 65 in collapsed condition.

4. A collapsible shipping crate comprising a bottom wall member having end and side walls hinged thereto upon horizontal pivots, a top wall member, means operatively 70 connecting said top wall member to the side wall members whereby manipulation of the top wall member will effect raising and lowering of said side wall members to their collapsed or expanded position, said side and 75 top wall members including transverse bars or rungs, and said means including loops slidably loosely connecting pairs of said rungs, the side walls of the crate further including longitudinal top rails, and the loops 80 being of angular formation so as to embrace said rails when the crate is expanded.

5. A collapsible shipping crate comprising a bottom wall member having end and side walls hinged thereto upon horizontal 85 pivots, a top wall member, means operatively connecting said top wall member to the side wall members whereby manipulation of the top wall member will effect raising and lowering of said side wall members to their collapsed or expanded position, said side and 90 top wall members including transverse bars or rungs, and said means including loops slidably loosely connecting pairs of said rungs, the side walls of the crate further including longitudinal top rails having transverse grooves therein, and the loops being of 95 angular formation so as to embrace said rails and rest in said grooves when the crate is expanded.

6. A collapsible shipping crate comprising a bottom wall member, side and end walls foldable upon horizontal pivots and carried by said bottom wall member, a top wall member, and means operatively connecting said side walls to the top wall member whereby the latter must and may be slid laterally in one direction and raised at one side and then slid laterally in the opposite direction and raised at the other side for 100 moving the side walls to a vertical position when the crate is expanded, or first slid laterally in one direction and allowed to fall at one side and then slid laterally in the opposite direction and allowed to fall at the 105 other side for moving the side walls to a horizontal position when the crate is collapsed.

In testimony whereof I affix my signature.
MICHAEL F. A. O'TOOLE.
